UNITED STATES PATENT OFFICE.

HARRY LANDSIEDEL, OF NORWOOD, OHIO, ASSIGNOR TO THE DALTON ADDING MACHINE COMPANY, OF CINCINNATI, OHIO, A CORPORATION OF OHIO.

ADDING MACHINE.

Application filed January 6, 1923. Serial No. 611,057.

This invention relates to adding machines. Adding and calculating machines are usually provided with connections for operation by motor or by hand levers, as conditions may require or as the user may prefer. To avoid confusion and prevent needless operation of parts it is desirable to prevent operation of the hand lever when the machine is operated by motor, and it is also desirable to prevent operation of the motor when the machine is to be operated by hand.

When error is made in setting up a number in the machine it is desirable to cancel or eliminate the number from the machine and to clear the setting up devices so that the correct number may be set up.

My present invention has special reference to mechanism for obtaining the above mentioned results, and an object of the invention is to prevent operation of the machine by the motor when the hand lever is operative, and vice versa, and at the same time permit operation of the hand lever to a limited extent to control the clearing or elimination of an error from the machine by the motor.

Another object of the invention is to provide improved means for controlling the full-stroke device of the machine for the above purposes.

Other objects will appear from the following description, reference being made to the drawings in which—

Fig. 1 is a view showing the present invention designed and adapted for use in a machine of the Dalton type and showing the parts in the position they occupy when the machine is under control of the motor and cannot be operated by the hand lever.

Fig. 2 is a similar view showing the main shaft and essential parts of the present invention in position to which they are moved by the motor.

Fig. 3 shows the parts when the hand lever is operated a short distance, leaving the remaining operation to be performed by the motor in order to clear or eliminate an item from the machine.

Fig. 4 is a view showing the parts adjusted to permit operation of the machine by the hand lever.

Fig. 5 is a fragmentary view showing the full-stroke pawl disabled.

Fig. 6 is a similar view showing the full-stroke pawl effective.

The general construction and mode of operation of the differential and adding mechanisms of adding machines are familiar and one type of motor mechanism for operating adding machines is disclosed in my prior Patents No. 1,209,858, dated December 26, 1916, and No. 1,270,845, dated July 2, 1918. For present purposes it is sufficient to mention that the lever 1 is arranged to be oscillated by the motor connections (not shown) under control of a key 2 adjacent to the keyboard of the machine. The lever 1 engages a lever 3 attached to the rock shaft 4 of the machine, operation of which is necessary for each adding operation of the machine. The shaft 4 is also equipped with a hand operated part 5 whereby said shaft may be rocked to operate the machine independently of the motor.

The part 5 is connected to the shaft 4 in a familiar manner which permits the shaft 4 to rock forwardly independently of the part 5 and which rocks the shaft 4 from the part 5 when the latter is operated. This connection comprises a clutch, one member of which is on the shaft 4 and the other member of which is on the part 5 in the relationship that the shaft 4 can turn from the position shown in Fig. 3 to the position shown in Fig. 2 without movement on the part of the part 5; and the part 5 cannot turn in a counter-clockwise direction (Fig. 4) without turning the shaft 4.

It is well known that the motor is caused to operate by depressing the key 2. The key 2 may be locked against operation in which case the machine is wholly under control of the manual operating means including the part 5, or the part 5 may be locked against effective operation in which case the machine is wholly under control of the motor. The key 2 is attached to a rock shaft 6 having the usual motor controlling connections. A detent device 8 has a shoulder 9 that may be held in a raised position above an arm 10 on the shaft 6 to permit rocking of the shaft 6 by the key 2, or that may be de-

pressed to position shown in Fig. 4 to prevent depression of the key 2 and thereby prevent operation of the machine by the motor. A slide 11 has a depending part 12 for depressing the detent device 8 to the position shown in Fig. 4. A knob 13 is provided for operating the slide 11.

The mechanism as described is familiar in the Dalton adding machine and constitutes a part of the subject matter of my co-pending application Serial No. 472,390, filed May 25, 1921, patented August 28, 1923, No. 1,466,306. The present invention comprises a novel form of full-stroke mechanism and devices for controlling the same and, in addition, comprises means for utilizing a partial operation of the part 5 when the machine is under control of the motor. The notched segment 14 is rigid upon a lower support 15 and an upper support 16, the inner edge of the segment 14 being concentric with the axis of the shaft 4. An arm 3 rigid with the shaft 4 supports a full-stroke pawl 17 controlled by a spring 18 so as to ride against the notched inner edge of the segment 14 to require a full stroke before the direction of movement of the parts can be reversed after having once started. An arcuate plate 19 is positioned at the side of the segment 14 and has its lower end pivoted upon a support 20 and its upper end formed with a slot 21 receiving the rigid pivot 16. A roller 22 on the pawl 17 rides upon the inner curved edge of the part 19 when the latter is in its forward adjustment (Figs. 2 and 3), that is when the parts are adjusted for operation of the machine by the motor, and prevents the pawl 17 from engaging the notches in the segment 14. A lever pivoted on the pivot 16 has an arm 23 having pin and slot connections 24 with the plate 19. An arm 25 of said lever has a roller 26 cooperating with a link 27 the forward end of which is pivoted to the slide 11 and the rear end of which is supported upon a pin 28 extending through a slot 29 in said link. When the link 27 is pushed rearwardly by the slide 11, as when the latter is moved to the position shown in Figs. 1, 2 and 3 to place the machine under control of the motor, the arm 25 is raised and the arm 23 is depressed thereby moving the plate 19 forwardly to position to be engaged by the roller 22 and to prevent the pawl 17 from engaging the notches in the segment 14. The lever 23-25 also has an arm 30 which serves as an abutment stop for a projection 31 on the lever 5 to permit limited operation of said lever 5 but to prevent complete operation thereof when the machine is under control of the motor, that is when the parts are in the position shown in Fig. 1. When the slide 11 is moved forwardly to depress the detent device 8 to lock the motor key 2 against operation, the spring 32 draws the

lever arm 30 out of the way of the projection 31 and causes the lever arm 23 to move the plate 19 out of position to be engaged by the roller 22 (Fig. 4). This restores the effectiveness of the full stroke device, locks the motor key 2 against operation and permits operation of the hand part 5.

It will be seen that when the machine is under control of the motor (Fig. 1) the hand operated part 5 is capable of movement to a limited extent before the projection or knob 13 strikes the lower end of the lever arm 30. This limited rocking movement of the shaft 4 is sufficient to utilize the usual restoring devices (not shown) to clear or eliminate an item from the differential mechanism without printing the number or introducing it into the adding mechanism.

From the foregoing it will be seen that my invention is of a highly efficient construction and arrangement and obtains all of its purposes and functions in a satisfactory way. Numerous variations may be made in the arrangement and formation of the parts without departure from the nature and principle of the invention.

I do not restrict myself unessentially, but what I claim and desire to secure by Letters Patent is:

1. In a machine of the character described, the combination of a rock shaft, a motor lever for turning said shaft in one direction, devices controlling the operation of said shaft by said motor lever, a hand lever for turning said shaft in the same direction that the motor lever turns it, means settable to prevent operation of said devices or said hand lever as desired, and a full-stroke device for said shaft and said hand lever controlled by said last-named means.

2. In a machine of the character described, the combination with a part to be operated, a motor lever for operating said part independently of the hand lever, and a hand lever for operating said part independently of the motor lever, of a device settable independently of said hand lever to prevent operation of said part by the motor lever when it is desired to operate said part by the hand lever, a full-stroke pawl supported by said part to be operated, a stationary segment to be engaged by said pawl, and means for preventing said pawl from engaging said segment.

3. In a machine of the character described, the combination with a part to be operated, a motor lever for operating said part independently of the hand lever, a hand lever for operating said part independently of the motor lever, and a full-stroke device for said hand lever, of a device settable to prevent operation of said part by the hand lever and to disable said full-stroke device when it is desired to operate said part by the motor lever.

4. In a machine of the character described, the combination with a part to be operated, a motor lever for operating said part independently of the hand lever, a hand lever for operating said part independently of the motor lever, and a full-stroke device arranged to function when said hand lever is operated, of a device settable to prevent operation of said part by the hand lever and to disable said full-stroke device when it is desired to operate said part by the motor lever and also settable to prevent operation of said part by the motor lever and to restore said full-stroke device to effective condition when it is desired to operate said part by the hand lever.
5. In a machine of the character described, the combination with a motor lever, an element to be operated, connections for controlling the intermittent operation of said element by the motor lever, a hand lever for operating said element, and a full-stroke device for said hand lever, of a part settable to prevent operation of said connections leaving the hand lever free to operate and leaving said full stroke device effective, and a part settable to prevent operation of said hand lever and to render said full-stroke device ineffective and leaving said connections free to operate.
6. In a machine of the character described, the combination with a motor lever, an element to be operated, connections for controlling the intermittent operation of said element by the motor lever, a hand lever for operating said element, and a full-stroke device for said hand lever, of a part settable to prevent operation of said connections leaving the hand lever free to operate and leaving said full-stroke device effective, a part settable to prevent operation of said hand lever and to render said full-stroke device ineffective and leaving said connections free to operate, and means for controlling the setting of parts for the purpose aforesaid.
7. In a machine of the character described, the combination of a motor lever, a lever arranged to be intermittently operated by the motor lever, connections for controlling the intermittent operation of said second lever by the motor lever, a detent for preventing operation of said connections, a spring for moving said detent out of position to prevent operation of said connections, a manual device for moving said detent to position to prevent operation of said connections, a hand lever, a full-stroke device for said hand lever, and means controlled by said manual device for disabling said full-stroke device.
8. In a machine of the character described, the combination of a rock shaft, a lever for turning said shaft in one direction and arranged to permit the shaft to be turned independently thereof while the lever remains stationary, an abutment movable to and from position to prevent complete movement of said lever and to permit less than full movement thereof, and means for controlling said abutment.
9. In a machine of the character described, the combination of a rock shaft, a lever for turning said shaft in one direction and arranged to permit the shaft to be turned independently thereof while the lever remains stationary, an abutment movable to and from position to prevent complete movement of said lever and to permit less than full movement thereof, means for controlling said abutment, and a full-stroke device for said lever that is effective when said abutment is out of position to prevent operation of said lever and ineffective when said abutment is in position to prevent operation of said lever.
10. In a machine of the character described, the combination of a rock shaft, an actuator for turning said shaft in one direction, a hand lever for turning said shaft in the same direction that it is turned by said actuator, a full stroke pawl supported from said shaft preventing return movement of the shaft until the handle is moved to full extent of movement, means settable to prevent operation of said shaft by said hand lever, and a device operated by said means for disabling said full-stroke pawl when the shaft is to be operated by the actuator.
11. In a machine of the character described, the combination of a rock shaft, a pawl pivotally supported by said rock shaft, a rigid segment having notches therein adapted to be engaged by said pawl, a hand lever for operating said rock shaft, a device settable to prevent operation of said rock shaft by said hand lever, and means controlled by said device to prevent said pawl from engaging the notches in said segment.
12. In a machine of the character described, the combination of a rock shaft, a manually operable part for turning said rock shaft from a starting position, a separate independently operable part for turning said shaft from said starting position while said manually operable part remains unoperated, a full stroke pawl pivotally supported by the rock shaft, a rigid segment having notches adapted to be engaged by said pawl when said shaft is turned by said manually operable part, an element settable to prevent said pawl from engaging the notches in said segment, and a device operable independently of said manually operable part to set said element to prevent said pawl from engaging the notches in said segment.
13. In a machine of the character described, the combination of a rock shaft, a manually operable part for turning said

- rock shaft from a starting position, a separate independently operable part for turning said shaft from said starting position while said manually operable part remains 5 unoperated, a full stroke pawl pivotally supported by the rock shaft, a rigid segment having notches adapted to be engaged by said pawl when said shaft is turned by said manually operable part, an element settable to 10 prevent said pawl from engaging the notches in said segment, a device operable independently of said manually operable part to set said element to prevent said pawl from engaging the notches in said segment, and 15 means preventing operation of said manually operable part when said element is in position to prevent said pawl from engaging said notches.
14. In a machine of the character described, the combination of a rock shaft, an actuator for turning said rock shaft in one direction, a lever for turning said shaft in the same direction that it is turned by said actuator, and means settable to limit extent 20 of movement of said lever to prevent complete operation of said rock shaft thereby when the shaft is to be operated by said actuator.
15. In a machine of the character described, the combination of a rock shaft, an actuator for turning said rock shaft in one direction, a lever for turning said shaft in the same direction that it is turned by said actuator, means settable to limit extent of 25 movement of said lever to prevent complete operation of said rock shaft thereby when the shaft is to be operated by said actuator, a full-stroke device, and means for disabling said full-stroke device when the shaft is to be operated by said actuator.
16. In a machine of the character described, the combination of a rock shaft, a lever for turning said shaft in one direction and arranged to permit the shaft to be 30 turned independently thereof while the shaft remains stationary, an abutment movable to and from position to prevent complete operation of said lever and to permit partial operation thereof, and means for moving said abutment to position to permit complete operation of said lever or to prevent complete operation and permit partial operation thereof.
17. In a machine of the character described, the combination of a rock shaft, a lever for turning said shaft in one direction and arranged to permit the shaft to be turned independently thereof while the shaft remains stationary, an abutment movable to 35 and from position to prevent complete operation of said lever and to permit partial operation thereof, means for moving said abutment to position to permit complete operation of said lever or to prevent complete operation and permit partial operation thereof.
18. In a machine of the character described, the combination of a rock shaft, a lever for turning said shaft in one direction and arranged to permit the shaft to be turned independently thereof while the shaft remains stationary, an abutment movable to and from position to prevent complete operation of said lever and to permit partial operation thereof, means for moving said abutment to position to permit complete operation of said lever or to prevent complete operation and permit partial operation thereof, a full-stroke device for said shaft and lever that is effective to require complete movement of said lever and said shaft when said abutment is in position to permit complete operation of said lever. 70
19. In a machine of the character described, the combination with a rock shaft having a starting position, a manually operable part for turning said shaft from said starting position, and a full stroke device for said shaft, of means operable independently of said manually operable part for turning said shaft from said starting position, an element requiring manipulation when said shaft is to be turned by said means, and connections settable to disable said full stroke device and prevent operation of said manually operable part. 95
20. In a machine of the character described, the combination with a rock shaft having a starting position, a manually operable part for turning said shaft from said starting position, and a full stroke device for said shaft, of means operable independently of said manually operable part for turning said shaft from said starting position, an element requiring manipulation when said shaft is to be turned by said means, connections settable to disable said full stroke device and prevent operation of said manually operable part, and means controlled by said connections in one position thereof to prevent operation of said element. 105
21. In a machine of the character described, the combination with a rock shaft having a starting position, and optionally operable parts for turning said shaft from said starting position, of connections settable in each of two positions, and devices controlled by said connections in one position to prevent operation of one of said optionally operable parts and to permit 125
- 130

operation of the other of said optionally operable parts.

22. In a machine of the character described, the combination with a rock shaft 5 having a starting position, and optionally operable parts for turning said shaft from said starting position, of connections set-

table in each of two positions, and devices controlled by said connections in one position to prevent operation of one of said optionally operable parts and to permit operation of the other of said optionally operable parts, and vice versa. ¹⁰

HARRY LANDSIEDEL.
